UNITED STATES PATENT OFFICE.

BERNARD S. NELSON, OF NEW ORLEANS, LOUISIANA, ASSIGNEE TO A. M. LOCKETT & CO. LTD., OF NEW ORLEANS, LOUISIANA, A CORPORATION OF LOUISIANA.

OIL HEATER.

1,427,408.

Specification of Letters Patent. Patented Aug. 29, 1922.

Application filed March 22, 1920. Serial No. 367,673.

To all whom it may concern:

Be it known that I, BERNARD S. NELSON, a citizen of the United States, residing at New Orleans, in the parish of Orleans and 5 State of Louisiana, have invented certain new and useful Improvements in Oil Heaters, of which the following is a specification.

This invention relates to heaters, and primarily to oil heaters for use in connection 10 with the preparation of oil supplied to oil burners.

The general principle of the invention is based on the porcupine tube effect where the liquid to be heated is made to pass through 15 an inner pipe and to return on the outside of this heater pipe in the form of a thin film between it and the hot outer pipe.

The main object of the invention is to increase the efficiency of this type of heater. 20 The efficiency of a tube type of heater varies as some function of the velocity of the liquid through the heater tube, and a high velocity with a minimum amount of heating surface is maintained in a multi-pass heater; the 25 drawing hereinafter referred to in detail, discloses a heater of the two-pass type, which doubles the velocity for any given number of tubes.

Another feature of the invention is the 30 heater head which comprises a single casting without any oil joints other than screw threads, and designed for a multi-pass effect. The pipes comprising the heater tubes are so mounted in this head that they will 35 be held concentric with respect to each other, and small guide ears forged on the outer ends of the inner pipes maintain them concentric throughout their length thus forming a passage of uniform thickness for 40 the oil film.

A further feature of the invention is the formation of the ends of the outer pipes of the heater tubes. The customary way to close these ends is to have a threaded joint 45 and a pipe cap screwed on. In accordance with this invention the ends of the pipes are squared to fit a socket wrench and a reinforcing block forced on the inside and afterwards welded at the extreme end. In this 50 way the tubes can be put much closer together than is possible when the pipe caps are used, besides obviating screwed joints.

Further details of the invention will ap-

pear as described in connection with the accompanying drawings, and hereinafter set forth and claimed.

In the drawings illustrating the invention, in which similar reference characters indicate the same parts in the several figures,

Figure 1 is a sectional view of an oil 60 heater constructed in accordance with this invention, showing parts in elevation.

Figure 2 is a detail elevation of the end of one set of tubes;

Figure 3 is an end view thereof; 65

Figure 4 is a longitudinal section on line IV—IV of Figure 2, and

Figure 5 is a transverse section on line V—V of Figure 4.

Referring to the drawings, 10 designates 70 the heater head for oil or any desired substances, which comprises a single piece casting which has no oil holes other than the screw threaded apertures for receiving the supply pipes and heating tubes generally 75 indicated as 11 and 12. This head has a threaded oil inlet opening 13; relief valve opening 14; and outlets 15 and 16. The interior of the head has partitions 17 and 18 which provide chambers 19, 20, and 21, 80 whereby a head is provided for a multi-pass heater, in this instance, a two-pass heater.

The heating tubes 11 and 12 comprise sets 85 of concentric pipes formed by inner pipes 22 and outer pipes 23. The pipes 22 are all mounted in the partitions 17 and 18, and the outer pipes are threaded into the inner portion 10' of the heater head 10. It will be noted that each set of tubes is held concentric at their inner ends by the concentric 90 arrangement of the threaded openings which support them at their inner ends, and the pipes are preferably all provided with glycerine and litharge packing or the like at their joints with the heated head and are 95 adapted to withstand the pressure of the oil within them.

The inner pipes 22 are maintained concentric within the outer tubes 23 at their outer ends by forging a plurality, preferably 100 three or more, guide ears 24 on their free or open ends, as shown best in Figures 4 and 5. The concentric arrangement of the tubes throughout their length, as will be readily seen, forms a uniform annular space between 105 the tubes for a film of oil or the like to pass

and the guide ears 24 allow the pipes 22 to slide within pipes 23 to take care of expansion and contraction of the apparatus.

The outer pipes 23 are squared at their outer ends 25 to fit a socket wrench and the distance between the diagonal corners of said squared ends is substantially equal to the diameter of the outer pipes 23; a square reinforced block 26 is forced in and the end 10 of the tube is welded by oxy-acetylene or any other similar process. Thus sealed ends are formed at all the ends 25, and the tubes can be placed closer together than they could ordinarily if they were provided with the 15 inner internally threaded pipe cap, for the reason that the outside corners of the square ends 25 will not require any more space than the circumference of the tube 23.

A heater shell 27 is fastened to the head 20 in any convenient manner. It is provided with threaded openings 28, 29, and 30, for the steam inlet, a safety valve, and an outlet for the steam and water of condensation within the casing. The casing is also provided with a baffle plate 31 for directing the steam over the heating tubes 11 and 12.

In operation of the heater, oil to be heated enters chamber 19 through the opening 13, passes through the pipes 22 of the tubes 11 30 and passes by way of the annular space between pipes 22 and 23 to chamber 19, thence through pipes 22 and 23 of tubes 12 to chamber 21 and out of the heater head by outlets 15 and 16. The tubes 11 and 12 are heated 35 by means of live steam or exhaust steam from any suitable source, passing into the casing 27 through the inlet 28 around the baffle 31 down and out through the outlet or drain 30.

40 It is obvious that the construction herein described and illustrated as the preferred embodiment of the invention is not limited to oil heaters but may be employed for other purposes, within the scope of the invention, 45 where any efficient heat or cold exchange or transfer device is desired, as for example a

water heater, steam or ammonia condenser, brine or oil cooler and whether the heat exchange tubes are vertical or inclined, or horizontal as shown.

50

What I claim is:

1. An apparatus for exchanging heat comprising a single piece head having inner and outer walls having threaded apertures therethrough and formed with partition 55 members extending between said walls and having threaded apertures therethrough concentric with each of the apertures in the inner wall of the head, tubes extending from the head consisting of outer pipes each 60 sealed at one end and having their other ends threaded into the apertures in the inner wall of the head, and inner concentric pipes having their inner ends threaded into the apertures in said partition members and 65 their outer ends provided with integrally formed and outwardly projecting ears whereby they will be maintained concentric with the outer tubes throughout their length, and a shell extending over the tubes fastened to the inner wall of the head and provided with inlet and outlet openings.

70

2. An apparatus for exchanging heat comprising a head having heating tubes extending therefrom and a shell extending from 75 the head and covering said tubes, said tubes comprising sets of inner and outer pipes mounted concentrically in the head, said inner pipes having their outer ends open and formed with outwardly projecting ears for 80 engaging the inner sides of the ends of the outer pipes and holding the pipes in concentric relation throughout their length, said outer pipes having their outer ends squared to a size the distance between the diagonal 85 corners of said squared ends being substantially equal to the diameter of the outer tubes, a reinforcing block forged in said end and the whole welded to form a practically solid sealed end.

90

In testimony whereof I affix my signature.

BERNARD S. NELSON.
